(57) CLAIM

The ornamental design for men's supported underwear, as shown and described.

DESCRIPTION

FIG. 1 is a front left perspective view of the men's supported underwear showing the new design;

FIG. 2 is a front elevational view of the men's supported underwear thereof;

FIG. 3 is a rear elevational view of the men's supported underwear thereof;

FIG. 4 is a left side elevational view of the men's supported underwear thereof;

FIG. 5 is a right side elevational view of the men's supported underwear thereof;

FIG. 6 is a top plan view of the men's supported underwear thereof; and,

FIG. 7 is a bottom plan view of the men's supported underwear thereof.

The broken lines in the drawings depict stitching and form no part of the claimed design.
